IGNITION SYSTEM FOR INTERNAL-COMBUSTION ENGINES

Marion Mallory, Detroit, Mich.

Application May 7, 1945, Serial No. 592,364

3 Claims. (Cl. 123—117)

1

This invention relates to an ignition timing control means for an internal combustion engine and in particular to an internal combustion engine which has an automatically operated governor throttle valve located between the throttle valve of the carburetor and the engine.

It is an object of this invention to produce an ignition timing control means for an internal combustion engine which is actuated by changes in the intake passageway pressures that gives the proper timing curve both when the engine is controlled by the carburetor throttle valve as well as when it is controlled by the governor throttle valve.

The figure shows a sectional view partly in elevation showing the mechanism of my ignition timing control means for internal combustion engines.

The parts of my invention illustrated in the drawing are referenced as follows: carburetor 1; intake passageway 2 having inlet 3 and outlet 4 to the engine, venturi 5, manually controlled throttle valve 6 of the butterfly type, valve shaft 7, governor throttle valve 8 of the butterfly type, governor valve shaft 9, orifice 10 in the venturi, orifice 11 adjacent to and on the engine side of throttle valve 6 when in idle position, orifice 12 on the engine side of governor valve 8, valve housing 13, conduit 14 between port 19 in housing 13 and orifice 12, conduit 15 between port 20 in housing 13 and conduit 16, port 17 in housing 13, piston 18 controlling ports 19 and 20, circumferential groove 21 in piston 18, compression spring 22 tending to move valve 18 toward the right, suction device 23 having suction chamber 24 connected with orifice 10 by conduit 16, diaphragm 25 connected to circuit breaker plate 26 by rod 27, compression spring 28, ignition distributor cam 29, circuit breaker 30.

It is understood that governor valve 8 can be automatically controlled by any of the well known governor mechanisms such as the engine driven centrifugal weight type of governor, the velocity type governor, or the intake passageway suction controlled governor shown in my copending application Serial No. 466,961, filed November 25, 1942, now Patent No. 2,381,550. The point is that governor 8 is automatically operated to control the engine at some desired governed speed.

The operation of my device is as follows: As shown, throttle valve 6 is in idle position. Orifice 11 is subjected to intake manifold vacuum which has drawn valve 18 to the left cutting off port 12 from suction device 23. Suction chamber

2

24 is in communication through conduit 16 with orifice 10 which is substantially at atmospheric pressure so that the spark is retarded. If valve 6 is open slightly beyond idle position, orifice 11 passes to the atmosphere side of valve 6 and spring 21 moves valve 18 to the right to now place suction chamber 24 in communication with orifice 12 which will cause the spark to advance. If carburetor throttle valve 6 is opened wide and the engine control taken over by valve 8, then orifice 12 will remain in communication with suction chamber 24 and the spark will be controlled by pressure conditions obtaining at orifice 12 as modified by the Venturi vacuum set up at orifice 10. While valve 18 is open, then as governor 8 moves toward closed position the intake passageway vacuum will increase but the full vacuum will not be imposed upon diaphragm 25 because orifice 10 now serves as an air bleed to orifice 12. Also as governor 8 moves toward open position the intake passageway vacuum will drop but the velocity through venturi 5 will increase so that the Venturi suction created at orifice 10 will prevent the vacuum in chamber 24 from dropping as low as the vacuum at orifice 12. Whenever valve 6 is closed, then the intake passageway suction moves valve 18 toward the left to cut off orifice 12 from the suction device and spark advance is now controlled by the Venturi suction at orifice 10.

I claim:

1. An ignition system for an internal combustion engine comprising an ignition timer, an intake passageway, a throttle valve in said intake passageway, a governor valve in said intake passageway on the engine side of said throttle valve, a device actuated by changes in pressure in the intake passageway for controlling the said timer to advance and retard the spark, an orifice in the intake passageway on the engine side of said governor valve, a conduit connecting said orifice with said pressure actuated device, a second orifice in said intake passageway on the engine side of said throttle valve when in idle position and on the atmosphere side of said throttle valve when partly open, a valve actuated by changes in pressure in the intake passageway for controlling fluid flow through said first mentioned conduit, said pressure actuated valve being subjected on one side to atmospheric pressure and on the other side to the pressure obtaining at said second orifice, a housing for said valve in communication with said second orifice whereby when the throttle valve is closed the intake passageway

suction acts through said second orifice to close said valve and shut off communication between the first orifice and the pressure actuated device to retard the spark timing and a venturi in said intake passageway positioned on the atmosphere side of the throttle valve, a third orifice in the venturi and a conduit connecting the third orifice and said pressure actuated device whereby when said throttle valve is open said valve opens communication between the first orifice and the pressure actuated device so that the intake passageway pressures on the engine side of the governor valve as modified by the pressure obtaining at said third orifice are utilized to control the ignition timer.

2. An ignition system for an internal combustion engine comprising an ignition timer, an intake passageway, a throttle valve in said intake passageway, a governor valve in said intake passageway on the engine side of said throttle valve, a device actuated by changes in pressure in the intake passageway for controlling the said timer to advance and retard the spark, an orifice in the intake passageway on the engine side of said governor valve, a conduit connecting said orifice with said pressure actuated device, a second orifice in said intake passageway on the engine side of said throttle valve when in idle position and on the atmosphere side of said throttle valve when partly open, suction controlled valve means controlling communication between said first mentioned orifice and the pressure actuated means, a conduit connecting said second orifice with said suction controlled valve means, said suction controlled valve means being subject to atmospheric pressure on one side and on the other side to the pressure obtaining at said second orifice whereby when the throttle valve is closed the suction controlled valve means responds to intake passageway suction to close off the first orifice from the pressure actuated device, a venturi on the atmosphere side of the throttle valve, a third orifice in the venturi, and a conduit connecting the third orifice and said pressure actuated device whereby when the throttle valve is wide open the pressure actuated device will be controlled by the suction in the intake passageway on the engine side of the governor valve as modified by the pressure obtaining at the orifice in the venturi.

50

3. An ignition system for an internal combustion engine comprising an ignition timer, an intake passageway, a throttle valve in said intake passageway, a suction controlled device connected to said timer for advancing and retarding the spark, an orifice in the intake passageway positioned at all times on the atmosphere side of the throttle valve, a passageway connecting said orifice with the suction controlled device, a second orifice communicating with the engine side of the intake passageway when the throttle is in idle position and with the atmosphere side of said intake passageway when the throttle is in partly or fully opened position, a governor valve positioned on the engine side of said throttle valve, a third orifice positioned on the engine side of said governor valve, a second passageway connecting said third orifice with the suction controlled device, and suction controlled valve means in communication with said second orifice for controlling communication between the third orifice and the suction controlled device, said suction controlled valve means being subject to atmospheric pressure on one side and on the other side to the pressure obtaining at said second orifice whereby when the throttle valve is in closed position the suction controlled valve means responds to intake passageway suction to shut off the third orifice from the suction controlled device and when the throttle valve is opened beyond idle position the suction controlled valve means responds to place the third orifice in communication with the suction controlled device whereby the suction in the intake passageway on the engine side of the governor valve is utilized to actuate the suction device for controlling the ignition timer.
